United States Patent Office

Des. 188,130
Patented June 7, 1960

188,130

INDUSTRIAL NOISE HAZARD METER

William Carl Stuckrath, Ross Township, Allegheny County, Pa., assignor to Mine Safety Appliances Company, Pittsburgh, Pa., a corporation of Pennsylvania

Filed Jan. 19, 1959, Ser. No. 54,220

Term of patent 14 years

(Cl. D52—1)

Fig. 1 is a front perspective view of an industrial noise hazard meter, showing my new design; and

Fig. 2 is a similar perspective view thereof, showing the opposite side and end.

The rear of the noise meter, not shown, is substantially plain.

I claim:

The ornamental design for an industrial noise hazard meter, as shown and described.
